* cited by examiner

Primary Examiner—Alan P. Douglas*Assistant Examiner*—Rosemary K. Tarcza(74) Attorney, Agent, or Firm—Banner & Witcoff, Ltd.(57) CLAIM

The ornamental design for a portion of a battery, as shown and described.

DESCRIPTION

FIG. 1 is a front view of a portion of a battery showing our new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective top view thereof; and,

FIG. 8 is a perspective bottom view thereof.

The even broken line showing the reminder of the battery in the FIGS. 1–8 is for illustration purposes only and forms no part of the claimed design.
